Patented Sept. 12, 1922.

UNITED STATES PATENT OFFICE.

LYNDON F. WILSON, OF CHICAGO, ILLINOIS.

APPARATUS FOR MOLDING COMPOUND.

Application filed August 29, 1921. Serial No. 496,227.

To all whom it may concern:

Be it known that I, LYNDON F. WILSON, a citizen of the United States, residing at Chicago, in the county of Cook and State of Illinois, have invented certain new and useful Improvements in Apparatus for Molding Compound, of which the following is a specification.

This invention relates to an apparatus for molding plastic compounds, and has more particular reference to the molding of what are known as "boiler compounds," which consist of chemical compositions adapted to be placed either in the locomotive tenders or directly in the boilers themselves for the purpose of counteracting certain undesirable constituents carried by the water in some localities and which are very injurious to the boilers and detrimental to their operation unless the water is treated with a compound.

Compounds of this general character are now marketed in the form of sticks adapted to be introduced directly into the boiler through a plug hole or in the form of bricks or blocks which are introduced into the tender or other source of water supply to the boiler. The sticks usually weigh about one pound and are sufficiently small in cross section to permit of their introduction into the boiler, and the bricks customarily weigh about five pounds.

Prior to my invention, it has been the practice to mold both the bricks and the sticks in individual molds of the requisite sizes and proportions. Obviously, however, the initial cost of the molds and the labor and expense involved in handling them makes the manufacture of the compound quite expensive.

One of the primary purposes of my present invention is to provide a bed over which the compound may be spread in large sheets or slabs, the bed being so constructed and shaped that when the slab has dried or become set, it may be loosened from the bed and then broken along predetermined lines of cleavage by simply tapping it with a hammer along these lines into bricks of the required size and also into sticks, if desired.

Another object of my invention is to provide an apparatus comprising a series of duplicate members which may be readily assembled to provide a bed of any desired size, which apparatus shall be very simple in con-

struction and economical to manufacture and 55 assemble.

Other objects and many of the attendant advantages of my invention will be readily appreciated as the same becomes better understood by reference to the following description when considered in connection with the accompanying drawings.

Referring to the drawings:

Fig. 1 is a fragmentary plan view of a mold bed employed in my method; 65

Fig. 2 is a sectional view on the line 2—2 of Fig. 1; and

Fig. 3 is a perspective view of a compound brick produced by my invention.

Referring now to the drawings more in 70 detail, it will be observed that my invention contemplates the provision of a corrugated bed upon which the compound in plastic condition is molded. The bed herein disclosed is of very simple construction, comprising two longitudinally extending angle irons 5 and 6 disposed in parallelism with their horizontal flanges projecting inwardly. These angles serve as supporting members for the bed proper and may rest upon any 75 suitable supports such as stringers or timbers 7.

The bed proper is composed of a series of angle irons 8 disposed in parallelism and in contiguous relation between the side members, the ends of the angle irons resting upon the horizontal flanges of the side members 5 and 6. It will be observed from Fig. 2 that the angle bars 5 and 6 are larger than the angle irons 8 so that the vertical flanges of 80 the bars project above the plane of the crests of the angle members 8, thus forming side walls for the bed between which the compound 9 may be distributed over the bed to a depth somewhat in excess of the depth of 95 the angles 8. The end angles are equipped with upright flanges 11 extending upwardly substantially flush with the tops of the supporting angles 5 and 6 and provide end walls for the mold. The supporting angles 5 and 100 6 are drawn together in close relation to the ends of the bed angles 8 by any suitable means, and in the present instance, I have shown a connecting rod 12 equipped with a turnbuckle 13 by which the members may be 105 drawn together and clamped against the end of the angles 8.

In molding with the improved apparatus

disclosed, the requisite number of bed angles 8 to produce the desired size of bed are laid upon the supporting angles 5 and 6, as shown in the drawings, and the whole structure 5 is then clamped together as explained. A mass of the compound in plastic condition is then distributed over the bed thus formed and its upper surface is smoothed off and reduced to a predetermined level by running 10 a straight edge 14 longitudinally of the bed along the upper edges of the supporting angles 5 and 6, as shown in Fig. 2. This fills all of the V-shaped channels formed by the corrugated bed and reduces the thickness 15 of the mass to a predetermined depth above the crests of the bed angles so that a large slab of the compound may be poured and molded at one operation. The bed angles 8 may obviously be of any desired length, 20 but preferably for convenience in manufacture, I make them longer than the desired length of bricks or sticks which are to be molded, and in the present instance, I have illustrated them as twice the length of 25 the desired brick. After the compound has been poured and smoothed as described, it is cut longitudinally of the bed along a central line, indicated by reference character 15. This cut may extend to the bottom of the 30 channels or may terminate above the bottoms since the material when hardened, can be readily fractured along the line of cleavage thus produced.

The compound is then permitted to set or 35 harden in a large slab, depending upon the size of bed employed and when it has sufficiently set, a tool is inserted at one side of the bed between the slab and the bed angles, whereby the slab may be brought up and 40 slightly lifted from the angles. Since the slab is of minimum thickness immediately above the crest of each bed angle, it will be obvious that these lines of minimum thickness afford lines of cleavage along which the hardened 45 compound will readily break. When the slab therefore has been lifted from the channels at one edge, a sharp tap of a hammer or other tool along one of these lines of cleavage will cause the compound to break along this 50 line, and in practice, I prefer to break the slab along every fifth line of cleavage, producing a brick 16 substantially as shown in Fig. 3. By this method, the entire slab may be quickly broken into bricks which may 55 then be packed for shipment.

Shipment of the compound in bricks is cheaper than shipping it in sticks since there is less liability of breakage and less packing is required. The compound therefore reaches 60 the consumer in bricks and if it is desired for use in the tender or other tank, a whole brick is dropped into the receptacle. Should it be desirable to use the compound in stick form, which can be inserted into the boiler itself, a brick may be readily broken into 65

sticks by simply tapping it with a hammer along the lines of cleavage in exactly the same manner that the bricks were broken from the large slab.

It should be manifest that in accordance with my invention the construction of a bed upon which a large number of bricks may be simultaneously molded is much cheaper than the cost of individual molds for each brick. Furthermore, the pouring and leveling of 70 the material can be accomplished much quicker and cheaper in a large bed than in the individual molds, and in addition, the removal of the material from the mold or bed can be effected much quicker and cheaper 75 than it can from individual molds which require that each mold be separately lifted and inverted to release the brick therefrom. My invention therefore contemplates the employment of standard angle irons for the 80 construction of the mold bed and provides an economical method which can be speedily carried out in the production of the composition, and affords a wide range of flexibility in that the large slab may be broken 85 into bricks of any desired size, and even into individual sticks if preferred. 90

It is believed that my invention and many of the inherent advantages will be understood and appreciated from the foregoing 95 without further description, and while I have shown and described a preferred method and apparatus, obviously the details thereof may be varied within considerable limits within the scope of the invention as 100 defined in the following claims.

I claim:

1. An apparatus for molding compound, comprising a plurality of supporting members, a series of angle bars disposed between 105 said members in parallel contiguous relation with their apices extending upwardly to form a corrugated bed, and means for holding said bars against displacement.

2. An apparatus for molding compound, comprising a pair of side members of angle formation, a series of angle bars disposed between and resting upon the horizontal flanges of said side members with the apices of said angle bars extending upwardly, and 110 means for clamping said side members against the ends of said angle bars to form a mold bed having a corrugated bottom with 115 sides extending above the crests of the corrugations.

3. A compound molding apparatus comprising a series of angular members arranged in contiguous and parallel relation with the closed angle uppermost to provide a mold bottom having alternate elevations and depressions, and means for holding said members against displacement. 125

4. A compound molding apparatus comprising a series of structurally independent similarly shaped angular members, and 130

means for supporting said members in inverted position so as to provide a mold bed adapted to receive a quantity of plastic material, said bed having alternate elevations 5 and depressions to produce corrugations in the lower face of said material.

5. A compound molding apparatus comprising a bed formed from a series of angle

members arranged in parallelism in inverted position to produce elongated parallel 10 grooves in the lower face of a slab of plastic material disposed thereover, and means for detachably holding said members in predetermined position.

LYNDON F. WILSON.
